LUGGAGE REINFORCING MACHINE AND
METHOD

Robert H. Plass, Upper Montclair, N. J., assignor
to The Daisy Products, Inc., New York, N. Y.,
a corporation of New York

Application June 26, 1948, Serial No. 35,476

33 Claims. (Cl. 93—36)

1

This invention relates more particularly to a method of and machine for reinforcing luggage, although in some aspects it can be used in connection with the method of manufacture of boxes or containers or parts thereof which require reinforcement in order to impart rigidity to them in whole or in part, and especially when suitably reinforcing luggage to render it practically non-collapsible, even though light in weight.

In the art of luggage manufacture, to which the invention more specifically relates, the invention embodies improvements over the machine disclosed in my previous patent in that art, which is No. 1,723,072, dated August 6, 1929. The machine disclosed by that patent, while useful in a restricted sense, applies reinforcements to the main bodies of handbags or the like, when they are held on a mandrel. However, such bag bodies must be held by hand upon and manipulated by hand on the mandrel of the machine, as they are of rather greater dimensions than the mandrel, so that they are loose around it, except in the area where they are thus held by hand.

Various objections to that machine are overcome by the present invention, principally in that in reinforcing a bag body or the like, it is fitted by hand upon the mandrel and then held snugly and securely thereon against movement, without the use of the hands of the operator of the machine, preferably by mechanical means while the bag or the like is being reinforced by suitable power means acting on the reinforcement. The reinforcement may be of strong fiber-board or of any other suitably strong material, preferably flexible.

Usually, but not necessarily, such bag or the like has a peripheral wall to be reinforced and such wall has a lining, the peripheral wall being composed of any suitable flexible material such, for example, as real leather or artificial leather, and the lining being of thin fabric such as silk, satin, rayon, or the like, and such wall and lining having been previously connected along their opposite running edges so as to provide a pocket between them wherein the reinforcement is to be forcibly and snugly inserted.

Also usually, but not necessarily, there has previously been inserted into such pocket, preferably by hand, a relatively shorter strip of reinforcement than the strip which the machine inserts, inasmuch as such shorter strip, located at the back of the bag, forms a part of the final reinforcement and constitutes a rather desirable medium to be gripped by certain parts of the machine while the longer strip is being inserted.

2

The various objects and functions of the invention will fully appear herein, the invention comprising the new method and certain features of construction and combinations of parts to be described and then pointed out in the claims, reference being had to the accompanying drawings illustrating preferred embodiments of the invention and in which:

Fig. 1 is a sectional side elevation partly in broken lines, and showing in full lines a shield or skirt which fits the outside of a bag in operative position and in broken lines in released position;

Fig. 2 is a rear elevation of the machine, parts in broken lines;

Fig. 3 is a front elevation, parts in broken lines;

Fig. 4 is a detail section on line 4—4, Fig. 2; Fig. 5 is a detail section on line 5—5, Fig. 1;

Fig. 6 is a broken-away detail view in elevation, looking in the direction indicated by arrow 6 in Fig. 2, and showing the cam-controlled power shut-off;

Fig. 7 is a section on the line 7—7, Fig. 6; Fig. 8 is a section on the line 8—8, Fig. 3;

Fig. 9 is a section on the line 9—9, Fig. 3, parts broken away and parts in broken lines, and showing the bag clamp;

Fig. 10 is an elevation partly in section on the line 10—10, Fig. 9;

Fig. 11 is a side elevation of the upper mandrel member and the bag clamp thereon;

Fig. 12 is a plan view of half of the upper mandrel member, partly in section, showing the bag clamp;

Fig. 13 is a section on line 13—13, of Figs. 9 and 11;

Fig. 14 is a section with parts in plan view, showing the lower mandrel member fitted with a reinforcing strip and the pusher about to apply the reinforcement to the bag;

Fig. 15 is a section similar to Fig. 14, showing the reinforcement as having been completed;

Fig. 16 is a detail view of the jaw of the pusher;

Fig. 17 is a perspective view to show in general a bag partly reinforced at the back and not entirely reinforced by the principal reinforcement;

Fig. 18 is a general perspective view to show the bag of Fig. 17 as having been fully reinforced;

Fig. 19 is an enlarged broken section showing more clearly how a bag is gripped between the lower mandrel member and a platen;

Fig. 20 is similar to Fig. 19, except to show the platen released;

Fig. 21 is a section with parts in elevation to show a modification of the machine;

Fig. 22 is a perspective view of the turntable shown in Fig. 21; and

Fig. 23 is a broken perspective view of details shown in Fig. 21.

Referring in particular to Figs. 1, 3 and 10, and for the sake of convenience, only, describing the machine in the upright position illustrated, although it is conceivable that the machine and its parts might be in other positions, it includes a mandrel consisting of an upper member 1 and a lower member 2, corresponding in size with each other, and when the mandrel members are cylindrical, they would both have the same radii, which is the case in the illustration.

The two mandrel members are more especially designed to have snugly fitted thereon by hand the main body of a bag or box of flexible material, which is first fitted over the lower member and then pulled up and fitted also on the upper member.

A tubular shaft 3 is free to turn within the closed top 4 of the upper mandrel member 1, such tubular shaft terminating at a spaced distance away from the closed bottom 5 of the lower mandrel member 2. A vertical centering shaft 6 is rigidly fixed to the machine frame, as later on described, and upon this the tubular shaft is adapted to turn.

The frame of the machine comprises a pedestal or base 7 which supports a strong upright or standard 8 of channel steel, which has its web 9 nearest the mandrel and its flanges 10 extending away from the mandrel. A casting 11 of general U-shape is secured to the upright 8, and comprises a top member or leg 12, a lower leg 13, and an outer end portion 14 connecting said legs together. The upper leg 12 is provided with a socket 15 into which there is securely keyed and fastened the centering shaft 6 on which the tubular shaft 3 is adapted to turn.

The centering shaft 6 is formed with an enlarged bearing member 16, which is located between the upper and lower legs, 12 and 13 respectively, of the top member and is for a purpose explained hereinafter. Depending from the leg 13 is a bearing sleeve 17 within which the tubular shaft 3 is adapted to turn, said sleeve being provided with a flange 18 through which pass set screws 19 which enter the top 4 of the upper mandrel member to support said member.

Depending from the flange 18 and passing through the top 4 is a bearing sleeve 20, also for tubular shaft 3, which terminates a short distance below the upper mandrel member 1. Fixed to the lower end of the tubular shaft 3 is an arm 21 which is located between the spaced apart upper and lower members of the mandrel to permit the arm to perform its function of applying reinforcements as hereinafter described.

The centering shaft 6 extends a distance below the tubular shaft 3, and thereon is positioned a weight member 22 having a hub 23 in which the shaft 6 loosely fits. Set screws 24 pass through the weight member 22 and are screwed to the bottom 5 of the lower mandrel member 2. In this connection reference can also be had to Figs. 19 and 20 which more clearly show the parts just referred to.

Now referring particularly to Figs. 3 and 9 to

13 inclusive, the upper mandrel member 1 is provided with an outer peripheral wall 25 and an inner wall 26. The two walls 25 and 26 are respectively provided with inwardly bent upper edges, 27 and 28 respectively, through which pass fastenings 29, that also pass through the top 4 of the upper mandrel member, from which the walls 25, 26 depend. Said walls are spaced apart a slight distance and provide a track 30 extending around the mandrel top 4.

The lower mandrel member 2, as shown best in Figs. 10, 14, 15, 19 and 20, has an outer wall 31 with an inwardly extending bottom flange 31a and the said member also has an inner wall 32 with an inwardly extending flange 32a. These flanges, 31a and 32a, are in contact with the closed bottom 5, and through said flanges and said bottom there pass set screws 33. Said set screws also pass into a flat ring 35 constituting a gripping member, the outer periphery of which corresponds with the outer peripheral wall 31 of the lower mandrel member.

It will be seen that the outer wall 31 and the inner wall 32 of the lower mandrel member are also spaced apart for a relatively slight distance so as to provide a track 34 which corresponds and coincides with the track 30 located in the upper mandrel member. The tracks referred to are for the purpose of guiding the flexible reinforcing strip as stated later on herein.

Figs. 3 and 8 illustrate mechanism cooperating with mandrel members 1 and 2, for the purpose of securing the main body of a bag or box to the mandrel. A bracket 36 is secured rigidly by set screws 37 to the web 9 of the upright 8 and is provided with a grooved guide 38 for receiving a toothed rack 39 adapted to be raised and lowered by means of a gear 40. Said gear is located on a shaft 41 which is journaled in bearings 42, 42 on bracket 36. A collar 43 fixed on shaft 41 holds gear 40 against bearing 42 so as to mesh with the toothed rack 39 which is guided in the grooved guide 38. Keepers 44, 44 are secured to the guide member 38 and overlap the rack 39 to hold it in position.

As shown in Figs. 1 and 2, upon the outer end of the shaft 41 there is fixed a large hand wheel 45 for the purpose of rotating said shaft, to raise or lower the rack 39, said wheel being provided with a square hub 46 rigidly secured to shaft 41. A toothed pawl or detent 47 is mounted on a pivot 48 which has bearing on the grooved guide 38, and that is provided with a finger piece 49 adapted to raise or lower the detent 47, which engages with a ratchet wheel 50 fixed on shaft 41.

Referring to Figs. 1, 3, 10, 19 and 20, there is mounted on the upper end of the rack 39 an armed carrier member 51 which is also shown in broken lines in Fig. 9. The arms of the carrier member are provided at their outer ends with sockets 52 through which pass posts 53 secured to the carrier member and rigidly secured to a platen or platform 54. As the posts 53 have a slight movement in the sockets 52, cushioning springs 55 are positioned in the said sockets for the purpose of cushioning the platen 54. The platen 54 extends out a little from the lower mandrel member, and when the mandrel members are cylindrical, the edge of the platen 54 extends around it at a greater radius.

When the platen 54 is elevated, it presses the bottom of a bag body against the ring 35, or some abutment means on the lower mandrel member 2, and the platen then holds the bag bottom 75 against shifting, as is demonstrated more clearly

in Figs. 19 and 20 and will again be referred to hereinafter.

In Figs. 1, 2, 3, 9-12 inclusive, and 19 and 20, it will be seen that to the edge of the platen 54 there is affixed an upwardly extending wall or skirt 56 which runs about halfway around the platen, fastenings 57 constituting the means for securing such wall 56. Said wall is also illustrated in Figs. 14 and 15, to be fully described hereinafter. This wall 56 is of a height to oppose the outer walls 25 and 31, respectively, of the mandrel members 1 and 2 when the platen 54 is raised, and when said walls are cylindrical as shown, the wall 56 is curved lengthwise, as shown, on a radius somewhat greater than the radii of walls 25 and 31, sufficiently to oppose the peripheral wall of a bag body fitted on the mandrel. The upper edge of the wall or skirt 56 is flared to form a lip 58 for the purpose of preventing said wall from causing damage to the surface of a bag body when the platen is being raised.

The mechanism for transmitting power to the arm 21 which applies reinforcement to a bag or other article, will now be described with reference to Figs. 1 to 7, inclusive. An electric or other motor 59 is located on the base 7, and over its pulley is trained a belt 60 which passes over a pulley 61 rigidly secured to a shaft 62 at some distance above the motor. A loose pulley 63 is also mounted on shaft 62. The casing 64 in which shaft 62 is journaled contains any suitable well-known speed-reducing gearing 65 which hardly needs to be detailed. A counter shaft 66, also journaled in casing 64 is driven by the speed-reducing gearing, said casing being mounted on a bracket 67 secured by bolts 68 to upright 8. A support 69 for the counter shaft 66 is secured by bolts 70 also to upright 8.

A pinion 71 on counter shaft 66 meshes with a large slow gear 72 which turns on a journal pin 73 fixed to the web 9 of upright 8. As shown more clearly in Fig. 5, a guideway 74 extends radially upon the outer surface of large gearwheel 72.

The guideway 74 is provided by means of an element having an eye 75, fixed over the pin 73 and provided with parallel ways 76, 77, the said ways being formed at their ends with outwardly extending lugs 78, 78 which are secured to the gear 72 by means of set screws 79. The ways or tracks 76, 77 are undercut to provide an undercut groove 80.

Extending upwardly there is a toothed rack 81, the lower end of which is fixed to an extension 82 in which is mounted a stem 83 having a head 84, which engages in the undercut groove 80 and which is adapted to travel therein when the gear 72 rotates.

Referring to Fig. 4 particularly, a pinion 85 is fixed on a transverse rotary shaft 86 which is journaled in a bearing member 87 passing through and fixed to web 9 of the upright 8. Said pinion is of a length at least twice the width of the rack 81. There is swiveled upon the shaft 86 a guidepiece 88 having a groove 89 in which the rack 81 is adapted to slide, said rack being confined on the guidepiece by a keeper 90. Upon the shaft 86 there is fixed an adjustable collar 91, for the purpose to be described hereinafter.

Referring to Figs. 1, 2, 3, 6 and 7, they disclose mechanism for shifting the driving belt from the fast pulley to the loose one.

The large gear 72 rotates in the direction indicated by the arrow at the right of Fig. 2 and is provided with a cam 92 which projects from a

sleeve 93 fixed on the hub 94 of gear 72. This cam operates when gear 72 has made one complete revolution. A projection 95 extends from a rock shaft 96, journaled in brackets 97, which are fixed to the flanges 10 of upright 8.

The web 9 of the upright is provided with an opening 98 through which the projection 95 extends inwardly in a position to be engaged by the cam 92. A helical torsion spring 99 surrounds the rock shaft 96 and the ends thereof are respectively engaged with one of the brackets 97 and with the projection 95. Said cam places spring 99 under tension when moving the projection 95 and the spring returns the projection to normal position for subsequent operation by the cam. Extending from one end of rock shaft 96 there is a lever 100 which is provided with a projecting pin 101. The projection 95, spring 99 and the lever 100 form what will be characterized as tripping means.

Means for shifting the driving belt from the fast pulley onto the loose pulley comprise a slide 102 having an upward projection 103 adapted to be engaged by the tripping pin 101. This slide 102 is mounted on a supporting plate 104 fixed on bracket 67. Cheek plates 105 and 106, located at opposite sides of the slide 102, are fixed to the supporting plate 104. The slide 102 is provided with a pair of studs 107 which provide a throat through which the belt 60 passes. A pair of spaced stops 108, 109 on that end of the slide which has the projection 103, restrict the sliding movement of said slide by striking the abutments formed by the cheek plates 105, 106 at that end of the slide.

Again referring to Figs. 1 and 3, the shaft 86 on which the adjustable collar 91 previously mentioned is located, also is provided with a bevel pinion 110 adjacent said collar and another bevel pinion 111, these pinions being adapted to engage with the toothed bevel gear 112. Gear 112 is fixed on the rotary tubular shaft 3 at a point below the bearing member 16 through which the shaft 86 passes. A hand lever 113 is pivoted to a bracket 114 located on the casting 11, while shaft 86 is provided with a stud 115 so engaged with the lower end of the hand lever 113 that said shaft may rotate. There is a downward lug 116 on the bracket 114 which is provided with a pair of holes 117 adapted to receive a removable locking pin 118.

Now referring to Figs. 9, 11, 12 and 13, there is illustrated the preferred means for strongly securing the periphery of a bag body to the upper mandrel member 1, and such means as a whole is preferably omitted from other illustrations to avoid possible confusion.

An arm 119 is mounted so as to fulcrum on a journal pin 120 which is stationary, inasmuch as it is rigidly fixed to the top 4 of the upper mandrel member. Said arm is provided at its outer end with a downward jaw 121 and also carries a pivot pin 122 for a hand lever 123 which is provided with a sleeve 124 journaled on pin 122. Extending laterally from sleeve 124 is a lug 125 so that the handle 123 and the said lug constitute an angular member or bell-crank. A pivot pin 126 is mounted in the lug 125 and supports a link 127.

Link 127 is provided with a longitudinal slot 128 at its inner end, which slot receives a fixed guide pin 129 which is located on the flange 18 previously referred to. A lug 130 on the outer end of link 127 receives an adjustable stem 131 which is carried at the outer end of a helical

tension spring 132. A nut 133 is screwed onto the stem 131 for the purpose of providing adjustment of the tension of spring 132, whose inner end is anchored to the guide pin 129. A companion jaw 134 to jaw 121 is rigidly secured to the top of the upper mandrel member and extends down outside of the wall 26 of said member.

The operation of the clamping means is as follows: Referring to Fig. 12, the clamping means is out of action, while in Fig. 9 it is shown in clamping position. Upon pressing the handle 123 towards the mandrel to the position shown in Fig. 9, the arm 119 is moved so as to move the jaw 121 towards the periphery of a bag body secured upon the mandrel, while at the same time the link 127 is operated, which places tension upon the spring 132, when the axis of pivot 126 has been moved past a line intersecting the axes of pivots 122 and 129, which line may be said to correspond with the line defined by section line 13—13. Such imaginary line also intersects the axis of the vertical shaft 6. When the axis of pin 126 has passed such imaginary line, the spring 132 exerts strong pressure upon the arm 119 having jaw 121, causing said jaw to strongly clamp the intervening local portion of the bag against the companion jaw 134.

Before the machine is operated, however, the adjustment of the main reinforcement in the bag to its first position, and thereafter the positioning of the bag body on the mandrel and the securing of the same on the mandrel must be accomplished.

First, the positioning of the bag body and its securing will be explained. The bag body is shown only in a general way in Fig. 14 as having had previously inserted between the outer periphery A thereof, or peripheral band or web, and the lining or web B a relatively short strip of reinforcing material C which usually stiffens the back portion of the bag. The sections in Figs. 19 and 20 do not pass through C. Strip C is indicated in broken lines in Fig. 17 and is not present in Fig. 20 as well as in Fig. 19. Beyond the area thus stiffened the material of which the bag is composed is illustrated as limp or unstiffened in the area D, Fig. 17. In Figs. 14 and 15 are also shown the elements A, B and C of the bag.

In Fig. 20, as also in Fig. 19, there is shown the outer covering E and the lining F of the side wall or bottom of the bag, which are to remain as they are. However, the edges of covering E and lining F are bound by a thick seam or binding G with the edges of the peripheral covering A and lining B. Binding G is exaggerated in the illustration for the sake of clarity. Such bag construction need not be further described as it is well known, so that in describing the machine illustrated it is to be understood that such a bag body as explained is the preferred article to be reinforced.

To prepare for the operation of the machine after the principal reinforcement has been positioned in the bag as hereinafter described, the main body of the bag is fitted on the mandrel by the operator by pulling its peripheral wall over the lower mandrel member 2 and then pulling it onto the upper mandrel member 1, until the binding or seam G of said body is against the ring 35 of mandrel member 2 as shown in Fig. 19. The fit is snug and the side wall is taut.

Having snugly fitted the bag body onto the mandrel, the operator can turn the hand wheel 45 clockwise to move the rack 39 and platen 54

toward the mandrel from the position shown in broken lines in Fig. 1, and shown in Fig. 20, to that shown in full lines in Figs. 1, 10 and 19. Then the platen 54 has pressed the binding or seam G of the bag against the ring 35 of the mandrel member 2 so as to hold the seam and the bag wall E, F against shifting. At the same time the skirt or wall 56 on the platen would be moved thereby opposite to the mandrel in an area opposite to where a portion of the bag was pre-stiffened.

When the bag body has been confined upon the mandrel by the platen 54 and its skirt or wall 56, the operator then moves the handle 123 of the bag 15 clamping means from the open position shown in Fig. 12 to the closed position shown in Fig. 9, thereby, as previously explained, bringing the tension spring 132 into action to strongly press a local portion of the pre-stiffened area of the bag 20 between the clamping jaw 121 and its stationary companion jaw 134. In this way the periphery of the bag is held against shifting on the mandrel.

After the principal reinforcement has been adjusted in the mandrel the motor 59 is started, 25 with the driving belt 60 on the fast pulley 61, thereby rotating large gear 72 at much reduced speed. As shown in Fig. 1, the elongated pinion 85 is in mesh with rack 81 at its outermost half and the adjustable collar 91 on shaft 86 abuts a 30 boss 91a on the casting 11 so that such shaft and pinion are fixed at the position determined by collar 91 and at the same time the bevel pinion 110 is in mesh with bevel gear 112.

When the shaft 86 is to be shifted by hand lever 35 113 to mesh pinion 111 with gear 112, the collar 91 is loosened and again set in abutment with boss 91a, which also shifts elongated pinion 85 to mesh with the rack 81 at its innermost half. The latter position is not shown, but it is possible 40 when the machine rotates the pusher 21 in the mandrel in opposite direction to that to be stated herein, in which case an outer wall 31 at the right of Fig. 14 is used together with an inner wall (not shown) to form a track, and clamping 45 means such as was described herein will be mounted on the upper mandrel member adjacent a gap 136, therein corresponding to gap 137, adjoining which latter the clamping means is shown as located on the said mandrel member. Gap or 50 opening 137 is shown in Figs. 1, 3, 11, 14, 15, and there is a corresponding gap or opening 137a in mandrel member 2.

As shown in Fig. 16, the operative end of the pusher 21 has a jaw 138, the outward tooth of 55 which has an inside bevel or slant 139 to facilitate the entering of the end of strip H into the jaw. This is desirable for although the strip H, preferably made of fiber board, is flexible, it is yet stiff enough not to readily enter the jaw 138 unless its end is deflected thereinto.

Before the machine is operated, the bag to be reinforced must be made ready with a strip H, preferably of fiber board, which is adjusted in the bag and manipulated while the bag is loose 65 on the mandrel. The strip H is of a greater length than the pre-inserted stiffening strip C and is of a width approximating the distance between the mandrel walls 4 and 5. To prepare to do the reinforcing before starting the operation 70 of the machine, it is believed that this can be done in more ways than one. However, the preferred steps will be described.

First, the strip H is placed in the bag and one end is inserted through the pocket I for a relatively short distance by hand—sometimes a little

more and sometimes a little less, depending upon the strength of the manipulator, the strip taking a curved shape just inside the area where the bag is pre-stiffened, if the bag is cylindrical, for at least it is shown as so shaped. The inserted end may be trimmed smaller to facilitate its entering pocket I.

Now place the bag and strip H on the mandrel so that the opposite free end thereof will be located at the gaps or openings 137, 137a, shown in Fig. 3, by pulling the bag up onto the mandrel. This will register the transverse edge of that end with the tracks 30, 34, which are shown in Fig. 10. Next, the bag is shifted or twisted around the mandrel to advance the strip H in said tracks toward the pusher 21 until the pocket I cannot go any further in that direction, as shown in Fig. 14.

Now, the clamp jaw 121 is operated to grip the bag at the pre-stiffened part shown in Fig. 14, and the machine is ready to operate on the pusher 21 after the platen and its skirt 56 are raised. The pusher advances short of the pocket I, as shown in Fig. 15, which allows enough of strip H projecting out of the pocket to more than match the overlap between the advanced end of said strip and the further end of strip C. The end portion of the strip H which is engaged by the pusher is usually of such length as to permit of some mutilation by the pusher, and trimming down to the desired amount, after the bag has been removed from the mandrel, to fashion the pusher-engaged end for overlap with the adjacent end of the strip C. Last, the bag is buckled or bent inwardly at such trimmed end of strip H so as to enter it under the bag lining and lap it over strip C.

In the operation of the machine the rotation of bevel gear 112, as previously referred to, turns the tubular shaft 3 in the mandrel and rotates the pusher 21 in the direction indicated by the arrow, from the position shown in Figs. 9 and 14 to that shown in Fig. 15, with the result that the reinforcing strip H is pushed along the tracks provided and fully inserted between the peripheral band A and lining B to reinforce the limp portion D of the bag body, indicated in Figs. 14 and 17, and fill out the body as shown in Figs. 15 and 18. In doing so the reinforcing strip H is pushed between the skirt or wall 56 on platen 54 and those portions of the outer walls of the mandrel which are adjacent such skirt. The skirt or wall 56 constitutes a guard to prevent the relatively strong reinforcing strip H from objectionably pushing outwardly and possibly damaging the outer peripheral covering or wall A of the bag body while keeping said covering under control.

When the rack 81 has reached the outward limit of its travelling movement the pusher 21 has also 60 reached the end of its pushing movement and, although the gear 72 continues its rotation in the same direction as when the strip H is being pushed, the pusher is retracted to its starting position, while when it reaches such position the cam 92 acts upon the projection 95 of the tripping means to release it from its tension and to cause the latter to act on and move the belt shifter 102 to normal position and in turn to shift the belt from the fast pulley 61 onto the 70 loose pulley 63, thereby bringing the mechanism operated by the fast pulley to rest. The motor can now be shut off if desired and the machine prepared to reinforce another bag body.

A modification of the machine is illustrated in

Figs. 21, 22 and 23, wherein the platen or platform 140, the rotary tubular shaft 141 and the weight member 142 remain the same as before. The upper mandrel member previously used simply remains idle. The construction shown is adapted to apply a reinforcing strip of fiber board between the peripheral outer material and the lining of a cover for the described bag body, which cover has similar material and a lining extending throughout the area surrounded by the peripheral material. In this case a reinforcing strip is employed which is narrow, yet wide enough to render the peripheral material and its lining taut when fully inserted between it and the lining, and the strip used can be long enough to fully extend around the circumference of the cover and to somewhat overlap at its ends.

In this modification the pusher 143 is the same as the other one except that it needs no jaw, as there is secured to its outer end an elongated element 144 which extends from the pusher as a downward finger 145. A mandrel 146 of less depth than the lower mandrel member previously described takes the place of the latter, and the platen 140 grips the flat side of the cover only around the edge portion thereof. Such mandrel 146 is of slightly greater diameter than the previously described lower mandrel member.

Mandrel 146 comprises outer and inner walls 147 and 148, respectively, to form a track between them of about the length previously described, while around the other half of the mandrel there extends only the outer wall 147. The pusher finger 145 is entered between the walls 147, 148, to engage and push the reinforcing strip which is to be first adjusted in the track.

A turn table or plate 149 is provided with a notch 150, through which the pusher finger 145 extends. The said table is so supported as to turn close to the edges 151 and 152 respectively of the walls 147 and 148, and is of annular shape provided with re-bent legs 153 having inwardly projecting lips 154, which bear on the closed bottom 155 of the mandrel supporting the walls 147 and 148.

Before operating this modified machine the bag cover is snugly placed upon the mandrel 146 and the reinforcing strip is placed in the track defined by the walls 147 and 148 while the turn table 149 is held upward and the platen 140 and the mandrel 147 are in lowered position. Also, the advance end of the reinforcing strip is inserted into a pocket in the lining of the periphery of the cover such as previously described, and its opposite end within the track is adjusted to eventually contact with pusher finger 145 when the mandrel is in raised position.

Now, when the platen and the mandrel are moved upwardly by the elevating mechanism previously described, the mandrel will be brought into operative relation to the turn table which had been held upwardly, the presser finger will be caused to enter between the walls 147, 148, and the surrounding seam of the bag cover will be gripped, against shifting, between the edge portions of the platen and the bottom of the mandrel. Also, when the mandrel has been raised, the lips 154 of the turn table will be engaged in a circumferential groove 156 in the weight member 142, thus holding the turn table down while the lips travel in said groove. Thereby the reinforcing strip is held down.

The motor can now be started so as to cause the

pusher 143 to force the reinforcing strip in between the peripheral material of the cover and the lining thereof for a distance of about half the circumference of the bag cover. That being accomplished, the pusher will have returned to its original position, with the operating mechanism brought to rest. If the platen pressure is eased, the mandrel with the bag cover thereon turned around by hand until that length of the strip which has not been inserted contacts with the presser finger 145, and the platen pressure resumed, the driving belt of the motor can be quickly moved back onto the fast pulley, which will again cause the pusher 143 to advance the reinforcing strip into the remaining half of the bag cover sufficiently to cause a short overlap of the ends of the strip. The pusher having returned to its normal starting position, the mechanism will be brought to rest, so that the reinforced bag cover can now be removed in an obvious manner.

As in some of the claims on the machine itself the term "walls" is used, it is stated that such term is intended to characterize the track defining flanges of the mandrels and the skirt of the platen or the equivalents as walls.

It will be obvious to those skilled in the art that various changes and additions can be made in the described machines, without departing from the spirit of the invention and the scope of the appended claims.

What I claim as new is:

1. A machine of the class described, including a supporting frame, a mandrel mounted on the frame for receiving an enclosing member of a bag or box of flexible material having a side wall and a peripheral wall provided with a lining, such mandrel adapted to have the enclosing member snugly fitted on the periphery thereof, with the side wall against another surface of the mandrel, means mechanical on the mandrel for securing the enclosing member against shifting with respect to the mandrel, such means located at a spaced distance from said other surface of the mandrel and adjacent to the opening for the cover of the enclosing member, and means for forcibly pushing a strip of flexible reinforcement in between the lining and the peripheral wall for substantially the entire length of such strip while the enclosing member is thus secured.

2. A machine according to claim 1, wherein the securing means includes a clamping element on the mandrel operable against a pre-stiffened portion of the enclosing member of the bag backed up by an abutment on the mandrel.

3. A machine according to claim 1, wherein the securing means includes a clamping element on the mandrel, a spring adapted to press the clamping element into securing position, and operating means adapted to cause the spring to act and to overcome the spring action.

4. A machine of the class described, including a supporting frame, a mandrel mounted on the frame for receiving an enclosing member of a bag or box having a flexible side wall and a flexible peripheral wall, each wall provided with a lining, and the mandrel adapted to have the enclosing member snugly fitted thereon, a platen cooperating with the mandrel to hold the side wall against the mandrel, operating means to move the platen to holding position and in the opposite direction, and means for forcing a strip of flexible reinforcement between the peripheral

wall and the lining, whereby to reinforce the enclosing member.

5. A machine according to claim 4, wherein the platen operating means includes a rack bar extending from the approximate center of the platen, and a rotatable gear meshing with the rack bar.

6. A machine according to claim 4, wherein the platen operating means includes geared elements, a pawl and ratchet device to control such elements, power means to positively move the ratchet and geared elements, and means to release the pawl from the ratchet and permit the platen to move away from the mandrel.

7. A machine according to claim 4, wherein cushioning means are interposed between the platen and the operating means thereof.

8. A machine of the class described, including a mandrel onto which an enclosing member of a bag or box having a lining may be snugly fitted, and means for forcing a strip of reinforcement between the enclosing member and lining comprising a strip-feeding rotary element, gearing operable on the rotary element to feed the reinforcement the required amount, power means to operate the gearing such amount, and means controlled by the power means to automatically return the forcing means to position for operation on a reinforcement for a succeeding enclosing member to be fitted on the mandrel.

9. A machine according to claim 8, wherein the gearing includes a toothed rack bar, and the means controlled by the power means automatically acts to return the forcing means and the rack bar to position for applying a succeeding reinforcement to another enclosing member.

10. A machine according to claim 8, wherein the gearing includes a toothed rack bar, and the means controlled by the power means automatically acts to return the forcing means and the rack bar to position for applying a succeeding reinforcement to another enclosing member, the power-controlled means comprising a cam-controlled device to idle the rack bar at the end of its reinforcement applying and return movements.

11. A machine of the class described, including a mandrel onto which an enclosing member of a bag or box having a lining may be snugly fitted, the mandrel having a vertical axis, a horizontal arm in the mandrel rotatable about such axis, and adapted to force a strip of reinforcement between the enclosing member and lining, gearing operable on the rotary arm to feed the reinforcement the required amount, the gearing comprising an upwardly extending toothed rack bar, power means to operate the gearing and raise the rack bar such amount, and means controlled by the power means to automatically discontinue the raising of the rack bar, and to cause the bar to return to lowered position, thereby returning the rotary arm to position for applying another reinforcement between the enclosing member and lining.

12. A machine according to claim 11, including also a vertically movable platen, and means to move the platen to and from the mandrel, the platen adapted to cooperate with the mandrel to secure a side of the enclosing member, and the platen provided with a peripheral wall for opposing the mandrel, between which wall and the mandrel the enclosing member and lining are confined during the reinforcement.

13. A machine of the class described, including a mandrel consisting of two members having spaced-apart mutually presented rims of substan-

tially equal radii around an axis in common with the two members, and the members having inner tracks defined by the rims and by inner rims of substantially equal radii around such common axis, the spaced-apart members adapted to have snugly fitted therearound the body of a bag or box having a flexible covering with a lining in the peripheral wall of the covering, and having a side wall within the peripheral wall, movable means adapted to secure such side wall against an outer surface of one of the members which surface is transverse of such common axis, a pusher between the two members and movable about the common axis, and power means leading through the other one of the members to the pusher, the pusher adapted to force a strip of reinforcement along the tracks and between the peripheral wall of the bag or box body and the lining thereof.

14. A machine according to claim 13, including clamping means located on such other one of the mandrel members adapted to positively secure the bag or box body against shifting by engaging a local area previously stiffened.

15. A machine according to claim 13, wherein the movable securing means is provided with a wall for closely opposing the two mandrel members and the periphery of the bag or box body fitted thereon.

16. A machine according to claim 13, including clamping means located on such other one of the mandrel members and adapted to positively secure the bag or box body in a local area against shifting, and a tension spring for acting on a movable clamping portion of the clamping means.

17. A machine according to claim 13, wherein the power means includes gearing comprising a bar movable longitudinally by one of the gears and extending in the same general direction as the common axis, and acting on another of the gears to deliver power to the pusher.

18. A machine of the class described, including means for snugly and securely holding the flexible body of a bag or box at the side wall thereof and around a lined periphery thereof, power means, a forcing member operable thereby for inserting a strip of reinforcement between such periphery and the lining, the power means comprising a belt shifter, a fast pulley and a loose pulley, a drive shaft from the fast pulley, a system of gearing leading from the shaft to the forcing member, a shifting element operable on the belt shifter, and means operated by one of the gears to trip the shifting element, such shifting element adapted to move the belt shifter to thereby transfer the belt from the fast pulley to the loose pulley when the insertion of the reinforcement has been completed by the forcing member.

19. A machine according to claim 18, wherein the tripping means includes a cam located on the side of the one gear specified.

20. A machine according to claim 18, including a pair of stops upon the belt shifter and an abutment between the stops to restrict the extent of movement of the belt shifter.

21. A machine according to claim 18, wherein the shifting element is provided by a pivoted member mounted to one side of the one gear specified.

22. A machine according to claim 18, including a rock shaft on which the shifting element is mounted, and a spring acting on the rock shaft to return the shifting element to normal position after the tripping means has operated.

23. A machine of the class described, including

means for snugly and securely holding a flexible enclosing member of a bag or box at a side wall thereof and around a lined periphery thereof, a forcing member for inserting a strip of reinforcement between such periphery and the lining, a motor operable to cause the forcing member to complete the insertion, means having the double function of transmitting the power of the motor to the forcing member and to idle such member, means for throwing the motor out of action upon the forcing member after the insertion of the reinforcement has been completed, and tripping means operated by the means having the function of throwing the motor out of action upon the forcing member, such tripping means so acting upon the motor throwing out means as to cut off the power of the motor exerted upon the forcing member.

24. A machine of the class described, including a mandrel upon which the body of a bag or box of flexible material may be fitted, the lined periphery of the body around the mandrel and the side wall of the body against a side surface of the mandrel, means for inserting a principal strip of reinforcement between the periphery of the body and the lining, between which the body has been partially reinforced, a clamping jaw for pressing against the partially reinforced portion of the body, an arm pivoted upon another side surface of the mandrel and provided with such jaw, manually operable means for moving the arm of the jaw to bring the jaw into contact with the partially reinforced portion, and a spring acting on the arm and adapted to strongly press the jaw upon the partially reinforced portion when the principal reinforcement is to be inserted in the bag or box body.

25. A machine according to claim 24, wherein the manual means resides in an angular member pivoted to the jaw arm at its elbow, one end of the angular member forming a handle, and including a slotted link to which the other end of the angular member is pivoted, a pin on the mandrel entering the slot, and the spring acting to shift the link and to strongly press the jaw upon the partially reinforced portion when the pivot of such other end of the angular member has been moved beyond a line intersecting such pin and the pivot of the aforesaid arm on the mandrel.

26. A machine according to claim 24, wherein the manual means resides in an angular member pivoted to the jaw arm at its elbow, one end of the angular member forming a handle, and including a slotted link to which the other end of the angular member is pivoted, a pin on the mandrel entering the slot, and the spring acting to shift the link and to strongly press the jaw upon the partially reinforced portion when the pivot of such other end of the angular member has been moved beyond a line intersecting such pin and the pivot of the aforesaid arm on the mandrel, the spring anchored at one end to the pin in the slot of the link and provided at the other end, which acts on the link, with means whereby its tension may be regulated.

27. A machine of the class described, comprising two materials securing members with separate coating walls, at least one of the walls 70 movable, means for placing the walls in mutually facing opposition to snugly hold and confine between them an article having two fabricated webs of yieldable material, and power operated means including a forcing element adapted to forcibly insert a reinforcement between the two

confined webs of yieldable material, whereby to stiffen and strengthen the article.

28. A machine of the class described, comprising a movable platen, two opposed outer and inner stationary walls thereon adapted to guide a strip of reinforcement between them, the inner wall serving to have an article to be reinforced snugly fitted thereon for substantially the distance around it and the outer wall serving for securing such article thereupon having two fabricated webs of yieldable material, and power operated means including a forcing element adapted to forcibly insert such guided reinforcement between the two webs of yieldable material, and the platen and the walls movable to cooperative relation with the power means, whereby to stiffen and strengthen the article.

29. A machine according to claim 28, including a movable wall to oppose the outer stationary wall and snugly secure and confine the article between them.

30. A machine of the class described, including a mandrel having an outer rim and an inner rim, the rims spaced apart to provide a track between them, the outer rim forming a continuous periphery of the mandrel, and the mandrel being hollow within the rims and having a side member extending over the area within one of the boundaries of the periphery, such mandrel adapted to receive the rimmed flat cover of a bag or box having a lining around the inner surface of the cover rim, the lined rim adapted to be snugly fitted around the periphery of the mandrel, with the flat portion of the cover fitted against the side member of the mandrel, means for pressing the flat portion against such side member, and power operated means for inserting a strip of reinforcement, guided in the track, between the cover rim and lining, the inserting means comprising a rotary pusher arm provided at its outer end with a laterally extending finger entered in the track to engage the reinforcement therein.

31. A machine according to claim 30, including a turn-table within the mandrel and also overlapping the edge of the mandrel adjacent the pusher arm, the pusher finger engaged with the turn-table, and means within the mandrel for centering and guiding the turn-table.

32. A machine of the class described, comprising a hollow mandrel on which a bag or box body

having a surrounding wall provided with a lining is adapted to be snugly and firmly secured, the lining having an open pocket into which one end of a body reinforcing strip may be inserted by hand, means for positioning and guiding the strip around within the mandrel when such body is secured on the mandrel, and a pusher in the mandrel adapted to engage the other end of the strip to advance the aforesaid one end of the strip and to push the strip through the pocket and between the surrounding wall and lining, the pusher provided with operating means to cause the same to force the strip forwardly, and a shield wall closely adjacent to that portion of the mandrel whereto the strip is to be forced between the mandrel and wall, the shield wall restraining the tendency of the strip to push outwardly against the bag or box body.

33. A machine of the class described, comprising a hollow mandrel on which a bag or box body having a surrounding wall provided with a lining is adapted to be snugly and firmly secured, the entire wall adapted to be snugly fitted on the mandrel and the lining having an open pocket, means for positioning a body reinforcing strip around within the mandrel and to register one end of the strip with the pocket, such strip having a tendency to straighten outwardly in the mandrel, a pusher in the mandrel adapted to engage the other end of the strip to advance the aforesaid one end of the strip, after the body has been shifted around the mandrel towards the positioning means to cause such one end of the strip to enter the pocket, the pusher provided with operating means to cause the same to force the strip through the pocket and between the surrounding wall and lining, and a shield wall closely adjacent to that portion of the mandrel whereto the strip is to be forced between the mandrel and wall, the shield wall restraining the tendency of the strip to push outwardly towards the bag or box body.
